United States Patent Office.

JOHN F. MERRILL, OF CINCINNATI, OHIO.

Design No. 4,954, dated May 30, 1871.

DESIGN FOR A FRUIT-CAN.

The Schedule referred to in these Letters Patent and making part of the same.

I, JOHN F. MERRILL, of Cincinnati, Hamilton county, Ohio, have invented and produced a new and original Design for a Fruit-Can, of which the following is a specification.

Description of the Accompanying Drawing.

The annexed drawing is a partially-sectionized elevation of a fruit-can embodying my design.

According to my improved design the body A of the can has a bulging shape, as shown at α α' .

The upper part is formed with successive shoulders B and C, and a neck, D, and the cover F has a corresponding shape, so that when in position it will form, in connection with the shoulders before referred to, a symmetrical series of steps.

To aid in sealing, a rim, E, is applied, in the manner represented.

The shoulder B serves to support and locate the

lower edge of the sealing-rim, and the ledge C forms the bottom of the sealing-trough.

The bottoms being left off enables my can to be "nested" very compactly for shipment to manufacturers and dealers.

Claim.

I claim as my design—

The combined conformation of the can-body A α α' , the shoulders B C, and cover F, as herein shown and described.

In testimony of which invention I hereunto set my hand.

JOHN F. MERRILL.
